UNITED STATES PATENT OFFICE.

ROBERT W. KALTENBACH, OF CLEVELAND, OHIO, ASSIGNOR OF ONE-HALF TO ERNEST J. KALTENBACH, OF BROOKLYN, NEW YORK.

CARBURETER.

1,072,733.

Specification of Letters Patent. Patented Sept. 9, 1913.

Application filed May 31, 1912. Serial No. 700,581.

To all whom it may concern:

Be it known that I, ROBERT W. KALTENBACH, a citizen of the United States of America, residing at Cleveland, in the county of Cuyahoga and State of Ohio, have invented certain new and useful Improvements in Carbureters; and I hereby declare the following to be a full, clear, and exact description of the invention, such as will enable others skilled in the art to which it pertains to make and use the same.

This invention relates to new and useful improvements in carbureters.

One object of this invention is to provide a carbureter having a very simple method of control and which at the same time has a far greater range of control than is possible with any of the old forms of carbureters.

Another object of my invention is to provide a carbureter which will furnish an extremely rich mixture on low motor speeds without danger of "loading up" or in any way interfering with the flexibility of the motor whereby great efficiency is attained and also a saving is secured in the consumption of gasolene.

With these objects in view and with the intention of securing other advantages which will hereinafter appear, my invention consists in the features of construction and combination of parts hereinafter described in the specification, pointed out in the claims and illustrated in the accompanying drawings.

In the accompanying drawings Figure 1 is a top plan of a carbureter embodying my invention. Fig. 2 is an end elevation of the same. Fig. 3 is a section on line 3—3, Fig. 2. Fig. 4 is a section on line 4—4, Fig. 1. Fig. 5 is a section on line 5—5, Fig. 1.

By referring to the drawings it will be seen that my carbureter consists of a body or shell which comprises a base portion 2, a cylindrical portion 3 of less diameter than the base portion which extends vertically from the center of the base portion so that the base portion extends beyond the cylindrical portion at diametrically opposite sides thereof. At the upper end of the cylindrical portion is arranged a top portion 4 which is of the same general shape as the base portion and projects beyond the cylindrical portion at diametrically opposite sides in line with the projecting portions of

the base. At the center of the top portion 4 is arranged a cylindrical neck portion 5 and at the upper end of the neck portion 5 is formed a flange 6. At one side of the cylindrical portion 3 is arranged a semi-cylindrical projection or extension 7. At each side of the top member 4 where it projects beyond the cylindrical portion 3 and from the under surface thereof a series of cylindrical members extend downwardly to within a short distance of the projecting portion of the base. There are three of these members at each side, the members at one side being indicated by 9, 10 and 14, and at the opposite side by 11, 12 and 13. A horizontally arranged cylindrical extension is formed integral with each series of the said downwardly extending members, shown at 15 and 16. The interior of the base portion 2 and the interior of the cylindrical portion 3 are in open communication and form a single chamber 17 which constitutes the reservoir chamber. The interior of the top portion 4 is separated from the interior of the cylindrical portion 3 by a wall 18 and the chamber 20 thus formed in the top portion constitutes the mixing chamber and this chamber is in open communication with the neck 5 through an opening 22. The chambers in the downwardly extending cylindrical members 9, 10, 11, 12, 13 and 14, indicated by 9', 10', 11', 12', 13', and 14', constitute the carbureting chambers and communicate at their upper ends with the mixing chamber 20 and at their lower ends with the outer air. A valve seat 23 is preferably arranged in the openings from the carbureting chambers to the mixing chamber 20.

In the top wall of the mixing chamber 20 in line with the openings from the mixing chamber into the carbureting chambers are formed a series of screw-threaded openings shown at 24, and in each of said openings is arranged a nut, said nuts being shown at 25, 26, 27, 28, 29 and 30. The nuts 25, 26, 27, 28 and 29 are similar, each having a chamber *a* and a small passageway *b* which places the said chamber in communication with the outer air. The nut 30 is provided with a straight bore *c* which extends through from end to end thereof.

On the base portion 2 where it projects at each side beyond the cylindrical portion 3 are mounted a series of nozzles 32, 33,

34, 35, 36 and 37, and each nozzle is arranged to extend up into one of the carbureting chambers 9', 10', 11', 12', 13' and 14'.

A valve is provided for closing each opening from the mixing chamber into the carbureting chamber. There are therefore six of these valves, shown at 42, 43, 44, 45, 46 and 47. These valves are all of different weight, the valve 42 being the heaviest and the valve 47 being the lightest valve. The valves 42, 43, 44, 45 and 46 are similar in form, the valve proper in each case being disk-shaped and having a centrally arranged upwardly extending stem, the stems of the valves being indicated by 42', 43', 44', 45' and 46'. These stems extend up into the chambers of the hollow nuts 25, 26, 27, 28 and 29 and fit snugly therein, but said stems do not extend to the tops of the chambers so that there is room for the stems to move up when the valves are raised. The valve 47 is also disk-shaped and is provided with a centrally arranged opening 47' and a tubular valve stem 48 extends downwardly therefrom into the carbureting chamber 14' and the lower end of the said valve stem 48 incloses the upper end of the nozzle 37. It will therefore be seen that all of the said valves are held on their respective seats simply by the action of gravity and that any suction created in the mixing chamber will tend to act on said valves and cause them to rise up from their seats, the lightest valve being lifted first and the other valves being raised in succession as the suction increases. In order to control the movement of the lightest valve 47 the following arrangement is provided:—In the bore *c* in the nut 30 is arranged a sleeve 50 which projects upwardly beyond said nut and is provided on its projecting end with a pair of ears 51 and is also provided with an exterior screw-thread. A nut 53 is screwed on the end of said sleeve and rests on the top of the nut 30. By screwing the nut 53 up or down on the sleeve 50 the sleeve 50 can be adjusted up or down within the bore *c* in the nut 30. A small rod 54 is arranged in the sleeve 50 and the lower portion thereof extends down into the tubular valve stem 48 but does not completely close the passageway in said valve stem. On the said rod 54, a short distance above the valve 47, is rigidly secured a stop-forming member 55. At the upper end of the rod 54 is formed a small head 56 and on said rod between the said head 56 and a shoulder 57 formed in the sleeve 50 is arranged a coil spring 58 which acts to hold up the rod 54 so that the said stop-forming member 55 is out of contact with the valve 47. At the top of the sleeve 50 between the ears 51 is pivotally mounted a small lever 59, the lower end of which is adapted to come in contact with the upper end of the rod 54 and is in the form

of a cam, the arrangement being such that when the lever is vertical the rod 54 will be in its upper position and when the lever is swung down the cam end thereof will shove down the rod 54 and bring the stop-forming member 55 thereon in contact with the valve 47. 70

In the neck portion 5 of the casing is arranged a throttle valve 60 which is provided with an operating handle 61 in the usual manner. 75

In each of the projections 15 and 16 at the sides of the carbureting chambers is formed a longitudinal bore shown at 15' and 16', and from the bore 15' passageways 63, 64 and 65 extend to the carbureting chambers 9', 10' and 14' respectively and from the bore 16' passageways 66, 67 and 68 extend into the carbureting chambers 11', 12' and 13' respectively. In the bore 15' is arranged a tubular valve 69 and in the bore 16' is arranged a tubular valve 70, and in the wall of each of said valves are formed three openings or slots, the openings in the valve 69 being indicated by 69' and the openings in the valve 70 being indicated by 70'. These slots are arranged circumferentially of the valve and are of different lengths and are so disposed that each slot will register with one of the passageways 95 leading into a carbureting chamber, and as they are of different lengths when a valve is rotated the longest slot will first come in registration with a passageway, then the next longest and then the shortest. The valves 69 and 70 are provided with operating arms 72 and 73 respectively. 100

In the extension 7 at the side of the cylindrical portion 3 is formed a valve chamber 7' which is in open communication with the reservoir chamber 17. A valve 75 is provided for controlling the inflow of gasoline through a feed opening 76, the said valve being controlled by a float 77 which is operatively connected with said valve, the whole being arranged in the usual manner and forms no part of my invention. The reservoir has a cleanout valve 78. 110

The operation of the carbureter is as follows: The feed opening 76 is connected with the gasoline tank and the flange on the neck of the casing is connected with the supply pipe of the engine. The gasoline will flow into the reservoir chamber until the raising of the float 77 closes the valve. The gasoline from the reservoir will rise in the nozzles to a predetermined height regulated by the float. The engine is then started and a suction will be created in the mixing chamber. If there is any difficulty in getting the engine started the little lever 59 is turned down which shoves down the rod 54 bringing the stop-forming member 55 in contact with the valve 47 which prevents the said valve 47 from being lifted 125 130 135

from its seat and therefore no air can enter but the pure gasoline will be sucked up through the tubular valve stem so that a very rich charge will be obtained. After 5 the engine has started the lever will be released and the suction will then raise the valve 47, it being the lightest valve and a mixture of both air and gasoline will enter the mixing chamber. If too much air is 10 admitted the nut 53 is turned so as to shove down the sleeve 50 which of course moves down the rod 54 and brings the stop-forming member closer to the valve 47, thereby limiting the upward movement of said 15 valve and reducing the quantity of air admitted. Now as the engine begins to run faster the suction in the mixing chamber will increase and the next heavier valve, that is the valve 46, will be lifted from its 20 seat and so on in turn, with the increase in suction, the valves 45, 44, 43 and 42 will be lifted until all the valves have been raised. If at any time it is found that the 25 mixture is too rich the valves 69 and 70 can be operated and additional quantities of air can be admitted to each of the carbureting chambers in succession. Under the action of the suction the gasoline will be drawn from the nozzle in tiny streams which will 30 shoot upward toward the mixing chamber and impinge against the valves which will produce an atomizing effect and air and gasoline will be thoroughly commingled before being drawn from the engine into the 35 cylinder of the engine. When the suction falls off the heaviest valve will be seated first, then the next heaviest valve and so on down to the lightest valve in case the engine is stopped. The provision of the air 40 space and the small outlet at the top of each nut tends to hold their valves on their respective seats and prevents their being jarred or lifted by the movement of the machine and the valves will therefore only 45 move when acted upon by the suction created in the mixing chamber.

What I claim is,—

1. In a carbureter, the combination of a reservoir for holding the gasoline, a mixing 50 chamber arranged above said reservoir and separated therefrom, a series of carbureting chambers communicating at their upper ends with said mixing chamber and at their lower ends with the outside air, nozzles 55 mounted on said reservoir and extending up into said carbureting chambers, the top wall of said mixing chamber being provided with openings in line with the openings from the mixing chamber into the carbureting chambers, chambered nuts arranged to close said 60 openings in the top wall of the mixing chamber, a series of valves of varying weights arranged in said mixing chamber so as to close the openings between the mixing chamber and the carbureting chambers, 65

each of said valves being provided with a valve stem which extends up into the chamber in the adjacent nut and means for supplying gasoline to the reservoir.

2. In a carbureter, the combination of a 70 reservoir for holding the gasoline, a mixing chamber arranged above said reservoir and separated therefrom, a series of carbureting chambers arranged in open communication at their upper end with said mixing chamber and at their lower ends with the outside air, the top wall of said mixing chamber being provided with screw-threaded openings in line with the openings from the mixing chamber into the carbureting 75 chambers, chambered nuts arranged to close said openings in the top wall of the mixing chamber, said nuts being provided with small openings in the walls thereof, valve seats arranged in the openings from the mixing chamber into the carbureting chambers, flat valves of varying weight arranged to rest on said valve seats, each of said valves being provided with a stem which extends up into the chamber in the adjacent 80 nut and a series of nozzles mounted on said reservoir and extending up into the said carbureting chambers, the openings in said nozzles being arranged under said valves, the arrangement being such that the fluid 85 drawn from the said nozzles when said valves are raised will impinge against the under surface of said valves.

3. In a carbureter, the combination of a 90 reservoir for holding the gasoline, a mixing chamber arranged above said reservoir and separated therefrom, a series of carbureting chambers communicating at their upper ends with said mixing chamber and at their lower ends with the outside air, nozzles 95 mounted on said reservoir and extending up into said carbureting chambers, a valve casing arranged at the side of said carbureting chambers, passageways extending from said valve casing to the carbureting 100 chambers, a tubular valve arranged in said valve chamber, said valve having an opening communicating with the outer air and having a series of circumferentially arranged slots of varying length arranged to 105 register with the said passageways from the valve casing to the carbureting chambers as the said valve is rotated, for the purpose set forth.

4. In a carbureter, the combination of a 110 reservoir for holding gasoline, a mixing chamber arranged above said reservoir and separated therefrom, a carbureting chamber communicating at its upper end with the bottom of the mixing chamber and at its 115 lower end with the outside air, a nozzle mounted on said reservoir and extending up into said carbureting chamber, an apertured valve arranged to close the opening from the mixing chamber into the carbureting 120 chambers, a valve having an opening communicating with the outer air and having a series of circumferentially arranged slots of varying length arranged to 125 register with the said passageways from the valve casing to the carbureting chambers as the said valve is rotated, for the purpose set forth.

chamber, said valve having a tubular stem extending down therefrom adapted to receive the upper end of the said nozzle, a rod extending down into the said tubular stem but not completely closing said stem and provided with a member arranged to be brought in contact with said valve so as to hold said valve upon its seat and means for raising and lowering said rod.

10 5. In a carbureter, the combination of a reservoir for holding gasolene, a mixing chamber arranged above said reservoir and separated therefrom, a carbureting chamber communicating at its upper end with the bottom of the mixing chamber and at its lower end with the outside air, a nozzle mounted on said reservoir and extending up into said carbureting chamber, a disk valve arranged to close the opening from the mixing chamber into said carbureting chamber, said valve being provided with a central opening, a tubular stem extending down from said valve, said stem being adapted to inclose the upper end of said nozzle, an opening formed in the top of the mixing chamber, a sleeve adjustably mounted in said opening, a rod extending down through said sleeve and having its upper end resting on top of said sleeve, the lower end of said rod being arranged to extend into the tubular valve stem and leave a clearance between the said rod and the inner wall of the said stem, a lever secured to said valve stem and adapted to raise and lower said stem and a member secured on said stem within the mixing chamber and adapted to be brought in contact with the said disk valve when the said

15 20 25 30 35

rod is lowered so as to hold said disk valve on its seat.

6. In a carbureter, a hollow base portion, a cylindrical portion extending upwardly from the base portion so that said base portion extends beyond said cylindrical portion at diametrically opposite sides thereof, the interior of the said cylindrical portion and the interior of the base forming a single chamber, a top portion arranged on the cylindrical portion and separated therefrom and projecting at diametrically opposite sides beyond said cylindrical portion, cylindrical members extending downwardly from the top portion where it projects at each side of the cylindrical portion, the interior of said top portion and the interior of said cylindrical members being in open communication, said top portion having openings in the top wall thereof, chambered nuts closing said openings, nozzles mounted on the base portion where it extends beyond the cylindrical portion and extending up into said cylindrical members depending from the top portion and valves arranged to control communication between the interior of said top portion and said cylindrical members, said valves being provided with stems which extend into said chambered nuts.

In testimony whereof, I sign the foregoing specification, in the presence of two witnesses.

ROBERT W. KALTENBACH.
